WITNESS:

HARRY J. MAAS
INVENTOR
BY Victor J. Evans
ATTORNEY

UNITED STATES PATENT OFFICE.

HARRY J. MAAS, OF CHICAGO, ILLINOIS.

ATTACHMENT FOR PENCILS.

Application filed October 1, 1923. Serial No. 665,971.

This invention relates to an attachment for pencils and has for its primary object the construction of an attachment whereby slips of paper or other articles may be conveniently carried upon the pencil.

An object of the invention is the provision of an attachment for carrying articles necessary in the use of the pencil.

Besides the above my invention is distinguished in the novel manner of constructing and associating parts so as to form a compartment while at the same time supporting a rubber tip which may be removed.

With these and other objects in view the invention will be better understood from the following detailed description taken in connection with the accompanying drawing wherein:

Fig. 1 is a side elevation of the attachment shown in applied position.

Fig. 2 is a sectional view on the line 2—2 of Fig. 1.

Fig. 3 is a sectional view on the line 3—3 of Fig. 1.

Fig. 4 is a sectional view on the line 4—4 of Fig. 1.

Again referring to the drawing illustrating one of the many constructions of my invention the numeral 1 designates a casing forming a compartment 2 having a neck portion 3 for engagement at the end of the pencil. This casing slidably receives a receiver 4 having one end open as indicated at 5 for the reception of the rubber tip 6.

The neck portion 3 of the casing serves in a secondary capacity to limit positioning of the receiver 4 with respect to the casing 1. The receiver is further provided with an opening 7 whereby ready access may be had to the paper slips 8 arranged in the compartment.

From the foregoing description taken in connection with the accompanying drawing it will be apparent that by sliding the receiver from the casing possession may be obtained of the paper slips so that notes may be made and the slips returned to the receiver for future reference.

In the drawing I have shown paper slips in the compartment but I wish it to be understood that when the attachment is connected to an automatic pencil, pencil leads may be arranged in the compartment.

It is, of course, to be understood that various other articles may be arranged in the compartment depending upon the practical use of the pencil.

It is, of course, to be understood that the invention may be constructed in various other manners and the parts associated in different relations, therefore, I do not desire to be limited in any manner except as set forth in the claim hereunto appended.

Having thus described my invention what I claim is:

An article of the class described including a casing open at one end and defining at the opposite end a reduced end portion for receiving an end portion of a pencil, and a receiver slidably received by the casing and including a longitudinal opening and a reduced end portion adapted to receive an eraser, said receiver and said casing being movable longitudinally in opposite directions with respect to each other to expose said opening, said reduced portion of said casing serving to limit positioning of the receiver with respect to the casing.

In testimony whereof I affix my signature.

HARRY J. MAAS.
